US00D960758S

(12) **United States Design Patent** (10) Patent No.: **US D960,758 S**
(45) Date of Patent: **** Aug. 16, 2022**

(54) **EARRING**(71) Applicant: **Venus by Maria Tash, Inc.**, New York,

NY (US)

(72) Inventor: **Maria Tashjian**, New York, NY (US)(73) Assignee: **Venus by Maria Tash, Inc.**, New York,
NY (US)(**) Term: **15 Years**(21) Appl. No.: **29/796,898**(22) Filed: **Jun. 28, 2021**

(56)
